CLEAT APPLYING TOOL

Edward H. Barron, East Orange, N. J.

Application March 21, 1950, Serial No. 150,947

5 Claims. (Cl. 1—47)

1

My invention relates to tools and more particularly to cleat applying tools.

In applying cleats to a supporting surface, considerable difficulty is experienced in maintaining both the object to be supported by the cleat and the latter in a predetermined location while fastening means, for instance, nails are driven through the openings in the cleat to secure the latter to the surface, an example of an installation of this character being the attachment of sections of pipe, in a definite spaced relation, to the ceiling of a room for utilization in connection with radiant heating.

One of the objects of my invention is to provide a cleat applying tool capable of supporting both the cleat and object in a predetermined position relative to a supporting surface for and during fastening of the cleat to the surface.

Another object of my invention is to provide a tool of the foregoing described character equipped with means effective for applying the fastening elements to secure the cleat to the supporting surface.

An important object of my invention is to provide a tool of the foregoing described character which is simple in construction, durable in use, efficient in operation and economical in manufacture.

With the above and other objects in view, as will hereinafter appear, the invention consists in the combination and arrangement of parts hereinafter set forth and illustrated in the accompanying drawings from which the several features of the invention and the advantages attained thereby will be readily understood by those skilled in the art.

Referring to the drawings wherein like reference characters designate like parts throughout the several views:

Figure 1 is a side elevation of my cleat applying tool.

Figure 2 is a top plan view thereof.

Figure 3 is a sectional view of the upper section of the tool, on an enlarged scale and taken on the line 3—3 of Figure 2.

Figure 4 is a detail sectional view taken on the line 4—4 of Figure 3.

Figure 5 is a perspective view of a cleat.

In the embodiment of my novel form of cleat applying tool or device illustrated in the drawings, I provide a head 5 formed with a pair of vertical bores 6 extending entirely through the head between its upper and lower ends and in which bores 6 are slidably and loosely mounted driving elements, rods or plungers 7 constituting

2

a pair of components of a driving assembly. The elongated upper face of the head is formed with an arcuate-shaped transverse slot 8 between the upper ends of the bores 6 and which slot 8 receives therein the intermediate arcuate portion 9 of a cleat C formed with relatively flat aligned end portions or feet 10 which extend over the upper face of the head 5 adjacent the slot 8.

The portions 10 of the cleat are formed with holes 11 which overlie the upper ends of the bores 6 and receive therethrough suitable fasteners, for example, nails N disposed on the upper ends of the rods 7. The nails N are driven by the rods 7 through the holes 11 as hereinafter more fully described, thus, securing the cleat C to a supporting surface, for instance, a ceiling S.

Each rod 7 is formed on its peripheral face, between its upper and lower end sections, with a flat 12 which cooperates with a set-screw 13, threaded into the head 5, for limiting the upward and downward movement of the rod. The rods 7 have their lower end sections normally disposed below the lower end of the head 5 as illustrated in Figures 1 and 3 of the drawings, for intermittent or driving engagement with an elongated cylindrical hammer or driver 15 constituting another component of the driving assembly.

Threaded within the lower end of the head 5, between the bore 6, is the upper end of a metallic supporting member or pole 16 on which the driver 15 is slidably mounted, the lower end of the pole being provided with a handle 17. The lower end section of the pole has reciprocally mounted thereon a hand grip 18 comprising a spirally wound member provided with an upper end section 19 extending in parallelism with the pole and terminating within a socket 20 formed in the lower radial face of the driver and secured within the socket by means of a set-screw 21.

The head has secured thereto an adjustable gauge 22 comprising an elongated bar 23 provided with a lengthwise extending row of spaced openings 24. A bolt 25 extends transversely through the head and selectively through one of the openings 24 in the bar and has threaded thereon a thumb-nut 26 which serves, when tightened against the bar 23, to maintain the latter in fixed relation with the head. One end of the bar terminates in a right-angularly disposed end section 27 which engages an adjacent object O for instance, a section of pipe, to position the cleat C in a desired spaced relation thereto. Obviously, by removing the nut 26, the bar 23 may be shifted to dispose the bolt 25 in any one of the other openings 24 to change

the distance between the object O and cleat C as desired.

It is to be noted that each of the rods 7 is of a greater length between its upper end and the upper end of the flat 12 than between its lower end and the adjacent end of the flat 12. This construction, when the rods are transposed end for end within the bores 6, permits the use of larger nails for securing cleats to the ceiling. It is also to be noted that the lower end of the pole 16 is adapted to extend an appreciable distance below the handle 17 so that when the device is quickly lowered or dropped from the ceiling, the lower end of the pole will initially engage the floor to preclude damage to the handle 17 by accidental engagement with the floor.

In use—assuming that nails are disposed within the upper ends of the bore 7 with their heads seated on the upper ends of the rods 7 and their shank ends extending through the holes 11 and terminating slightly above the legs 10, the cleat disposed over the head with its arcuate portion 9 set within the slot 8 and an object, for instance, a section of pipe P positioned within the cleat C—the head is lifted towards the ceiling by the pole 16 to dispose the cleat C and pipe P against the ceiling S and in spaced relation with the adjacent object O by means of the gauge 22. When the parts are thus positioned, the operator, with one hand gripping the handle 17, holds the head, cleat and pipe in fixed relation with the ceiling and with the other hand grasps the grip 18 and reciprocates the latter on the pole 16 with the result that the driver 15 engages the rods 7 and imparts a driving action therewith which drives the nails N into the ceiling through the openings 11 of the cleat C. When the cleat is thus applied to the ceiling with the section of pipe P secured therebetween, the device is lowered for further use in the same manner.

Without further elaboration, the foregoing will so fully explain the invention that others may, by applying current knowledge, readily adapt the same for use under various conditions of service. Moreover, it is not indispensable that all the features of the invention be used conjointly since they may be employed advantageously in various combinations and subcombinations.

It is obvious that the invention is not confined to the herein described use therefore as it may be utilized for any purpose to which it is adaptable. It is therefore to be understood that the invention is not limited to the specific construction as illustrated and described, as the same is only illustrative of the principles involved which are capable of extended application in various forms, and the invention comprehends all construction within the scope of the appended claims.

What I claim is:

1. In a cleat attaching device, a body having a cleat supporting face and formed with a plurality of bores opening through said face and an arcuate cleat positioning slot within said face and between said bores for accommodating therein the substantially U-shaped intermediate section of a cleat having relatively flat end sections provided with openings for disposal in substantial registry with said bores, a driving assembly including elements reciprocally mounted and re-

tained within said bores for driving cleat fastening elements contained within said bores through said openings to secure said cleat to a supporting surface.

5 2. The structure as set forth and defined in claim 1 including, a member connected to said body for positioning the latter in cleat applying position, and means carried by said body and slidably relative thereto for operating said assembly.

10 3. The structure as set forth and defined in claim 2 including, a gauge adjustably carried by said body for gauging the position of said body on said surface relative to an adjacent object or the like.

15 4. In a cleat attaching device, a head having a lower face and a cleat supporting upper face, said head being formed with a plurality of bores opening through both of said faces and with an arcuate cleat positioning slot within said upper face and between said bores for accommodating therein the arcuate-shaped intermediate section of a cleat having relatively flat end sections provided with openings for disposal in substantial registry with said bores, plungers slidably mounted and retained within said bores for driving nails disposed in said bores through said openings to secure said cleat to a supporting surface, said plungers having their lower end portions normally disposed appreciable distances below said lower face, and driving means connected to said head for engaging said portions to effect driving of said plungers.

20 5. In a cleat attaching device, a head having a lower face and a cleat supporting upper face, said head being formed with a plurality of bores opening through both of said faces and with an arcuate cleat positioning slot within said upper face and between said bores for accommodating

25 therein the arcuate-shaped intermediate section of a cleat having relatively flat end sections provided with openings for disposal in substantial registry with said bores, plungers slidably mounted and retained within said bores for driving nails disposed in said bores through said openings to secure said cleat to a supporting surface, said plungers having their lower end portions normally disposed appreciable distances below said lower face, a rod secured to said head and extending downwardly from said lower face for positioning said head in cleat applying position relative to said surface, and a driver slidably mounted on said rod for engaging said portions to effect driving of said plungers.

30 55 EDWARD H. BARRON.
